UNITED STATES PATENT OFFICE.

HARRY M. KNUDSEN, OF ST. PAUL, MINNESOTA.

DESIGN FOR A LAMP.

60,618.

Specification for Design. Patented Mar. 14, 1922.

Application filed February 4, 1921. Serial No. 442,489. Term of patent 7 years.

To all whom it may concern:

Be it known that I, HARRY M. KNUDSEN, a citizen of the United States, residing at St. Paul, in the county of Ramsey and State of Minnesota, have invented a new, original, and ornamental Design for Lamps, of which the following is a specification.

The figure is a front elevation of a lamp, showing my new design.

I claim:

The ornamental design for a lamp, as shown.

In testimony whereof I affix my signature.

HARRY M. KNUDSEN.
